UNITED STATES PATENT OFFICE.

FREDERICK DARLINGTON, OF PITTSBURG, PENNSYLVANIA, ASSIGNOR TO
WESTINGHOUSE ELECTRIC & MANUFACTURING COMPANY, A CORPORA-
TION OF PENNSYLVANIA.

MEANS FOR COOLING TRANSFORMERS.

No. 854,277.

Specification of Letters Patent.

Patented May 21, 1907.

Application filed June 25, 1906. Serial No. 323,366.

To all whom it may concern:

Be it known that I, FREDERICK DARLING-
TON, a citizen of the United States, and a resi-
dent of Pittsburg, in the county of Allegheny
5 and State of Pennsylvania, have invented a
new and useful Improvement in Means for
Cooling Transformers, of which the following
is a specification.

My invention relates to means for cooling
10 electrical transformers and other heat-pro-
ducing devices and it has for its object to pro-
vide means whereby heat may be dissipated
from such devices more efficiently and eco-
nomically than has heretofore been the case.

15 A problem that has heretofore presented
serious difficulties to engineers is that of dis-
sipating the heat produced in transformers
and other electrical translating devices that
supply power to railway and other distribut-
20 ing systems in hot climates where water is
scarce and expensive and where the tempera-
ture of the atmosphere, during a part of the
time, may be nearly as high as the safe-work-
ing temperature of the devices. One of the
25 prime requisites is that the stations should
not require constant attendance and care, so
that pumps, blowers and other artificial
means for causing circulation of a cooling
medium are in most cases prohibited.

30 According to the present invention, I pro-
pose to surround transformers and similar
devices with a medium having a high ther-
mal capacity in which heat may be stored
during the day, or at times when it is pro-
35 duced more rapidly than it can be dissipated,
and from which it may be radiated at night
or other times when the temperature of the
atmosphere is lower. The medium may also
serve to convey heat away at such a rate that
40 no other cooling means need be employed.

The single figure of the accompanying
drawing is a vertical sectional view through a
transformer that embodies my invention.

Located within a suitable receptacle 1 that
45 contains oil 2 or another suitable insulating
liquid, is a transformer 3 that is submerged
in the insulating liquid. The receptacle 1 is
located within a tank or reservoir 4, that may
or may not have a materially larger volume
50 than the receptacle, according to the amount
of heat which it may be necessary to store,
and that is filled with water or another liquid,

the specific heat of which is preferably high.
The reservoir 4 is preferably so mounted that
free circulation of air may occur over all its
surfaces, and if desired, it may be corrugated
or constructed in any suitable manner in
order to provide an increased superficial area
for radiation.

It will be understood that during the opera-
tion of the invention, heat is conveyed by the
oil from the transformer 3 to the receptacle 1,
from whence it is conveyed to the surface of
the reservoir 4 by means of the water. Since
the volume of the water is considerably
65 greater than that of the oil within the recep-
tacle, and also since the specific heat of water
is greater than that of oil, the water provides
a medium of greater thermal capacity than
the oil. If the volume of the water is suit-
ably proportioned to the conditions under
70 which the transformer operates, it will ab-
sorb and store the heat that is generated in
excess of that which may be dissipated imme-
diately, until conditions have moderated to
75 such an extent as to enable dissipation of the
heat at a greater rate than it is produced.
Water, besides having a higher specific heat
than oil, is also particularly suitable for the
purpose of providing a medium of high ther-
80 mal capacity because it will usually be
cheaper, even in arid climates, than oil and it
also reduces the fire risk. While, in general,
it will be more satisfactory to depend upon a
large superficial area for radiation to dissi-
85 pate the heat, it may be desirable in some
cases to employ other cooling means in addi-
tion, such as systems of piping in which wa-
ter or another cooling medium is circulated
artificially. As here shown, the reservoir 4
90 is provided with a cover 5 which substan-
tially prevents evaporation of the water, but
in some instances it may be desirable to em-
ploy open tanks or to remove the covers at
95 times in order that dissipation of the heat
may be aided by evaporation of the water.

I claim as my invention:

1. The combination with a receptacle con-
taining a heat-producing device and a liquid,
of a liquid in which the receptacle is immersed
having a greater thermal capacity than the
liquid within the receptacle.

2. The combination with a receptacle con-
taining a heat-producing device and a liquid,

of another liquid in which the receptacle is immersed having a higher specific heat than the aforesaid liquid.

3. The combination with a heat-producing device, a liquid surrounding the same, and a receptacle therefor, of a reservoir in which the receptacle is located, and a liquid contained therein having greater specific heat than the aforesaid liquid.

4. The combination with a heat-producing device, a liquid surrounding the same, and a receptacle therefor, of a reservoir in which the receptacle is located, and a liquid contained therein having a greater thermal capacity than the aforesaid liquid.

5. The combination with a heat-producing device, a liquid surrounding the same, and a receptacle therefor, of a reservoir of materially greater volume than the receptacle in which the heat producing device is located, and a liquid contained therein of greater specific heat than the aforesaid liquid.

6. The combination with a receptacle containing an electrical translating device and an insulating liquid, of a liquid surrounding the receptacle having a greater thermal capacity than the insulating liquid.

7. The combination with a receptacle containing an electrical translating device and an insulating liquid, of a liquid surrounding the receptacle having a higher specific heat than the insulating liquid.

8. The combination with a receptacle containing a heat-producing device and a liquid, of a substance surrounding the receptacle that has a greater thermal capacity than the liquid in the receptacle.

In testimony whereof, I have hereunto subscribed my name this 15th day of June, 1906.

FREDERICK DARLINGTON.
